HOOKED TOOL FOR TURNING OVER ENDS
OF RIVETSGeorge R. Phillips, New Brunswick, N. J., assignor
to Foster D. Snell, Inc., a corporation of New
York

Application December 13, 1946, Serial No. 715,967

4 Claims. (Cl. 218—19)

1

This invention relates to a crimping device for eyelets such as the metal grommets inserted as hollow bushings through holes in sheet material and then crimped. The invention relates, particularly, to a device or machine for blind crimping in which case the eyelet is accessible only from the outside as in crimping eyelets inserted through applied upholstery fabric. In this case the crimping device must be adapted to be inserted through the eyelet from the outside. It must include an anvil against which the outer end of the eyelet is held, a peening head to be inserted through the eyelet, and means for retracting the head in the direction of the anvil so that the end of the eyelet is upset.

The invention will be illustrated by description in connection with the attached drawings to which reference is made.

Fig. 1 is a side view partly in section of the crimping device showing the operating head inserted through an eyelet in a thin sheet.

Fig. 2 is a sectional view on line 2—2 in the direction of the arrows.

Fig. 3 is a view similar to that of Fig. 1 except that the peening head is in the crimping position.

Fig. 4 is a top plan view of a part of the assembly of Fig. 1.

There is shown a crimping machine having body portion 10, nose 12 and peening head 14, a fabric 15, and eyelet 17.

The nose and body are continuous with each other and the body, at its place of meeting the nose, is suitably shaped into an anvil portion 16 which extends around the base of the nose.

The body is of larger cross section than the nose and is provided with a longitudinally extending hole through which extends the plunger 18. Likewise the nose is provided with a slot 19. Likewise the nose is provided with a slot opening on the side of the nose and aligned with the said hole and of a width equal to the radius of said hole, this slot, shown at 20, receiving one end of the said plunger. It will be noted, as in Figs. 1 and 4, that the slot 20 and therefore the plunger 18 are offset with respect to the center line of the nose. The slot extends into the nose, from a side thereof, only to a distance equal approximately to the diameter of the plunger.

The peening head 22 at the forward end of the plunger is generally hook-shaped. Its width from the outside of the hook to the opposite edge, which is in line with an edge of the plunger, is no greater than and ordinarily is approximately equal to the maximum width of the nose 12. As shown, the peening head, when turned over the

nose as in Fig. 1, terminates at a position not beyond the side of the nose.

Means are provided for rotating and also retracting the plunger within the said hole and groove.

The rotation is effected by the lever element 24 that is suitably in the form of a half wing nut fitted over that end 26 of the plunger that extends through and beyond the body member 10. This fitting of the wing nut to the end of the plunger is effected by a squared portion 28 of the plunger holding the lever in substantially non-rotatable manner upon the plunger 18 and by the nuts 30 and 32 between which the wing nut is mounted so as to prevent its longitudinal movement.

When the half wing nut 24 is in the position shown by the solid lines of Fig. 1, then the peening head 22 extends over the nose of the crimping device and adapts the operating head of the device for insertion through the eyelet as shown in this figure. When the wing nut is rotated through 180°, to the position shown in the dotted lines 34 of Fig. 1, then the peening head is rotated also through 180° to the position of the dotted lines 36 in Fig. 1 or as shown also in Fig. 3.

Extending from the nose of the machine is a stop 38 against which the hook strikes when rotated to the closed position in which the hook extends over the nose and is in position for insertion through an eyelet.

Means for retracting the plunger with respect to the nose and the body of the machine, thus retracting also the peening head when extended to one side as shown in Fig. 3, include a pair of handles extending, as shown, in direction generally longitudinal with respect to the direction of extension of the plunger 18. One of these handles 40 is continuous with the body and the other 42 is mounted pivotally, as shown at 44, upon the handle 40. This handle at a midportion 46 contacts the nut 32 which is threaded and screwed on the plunger. When the handle 42 is pressed manually in the direction of 40, as to the position shown in Fig. 3, then the part 46 forces the nut 32 against spring pressure and also the lower end of the plunger in the direction that is downward in the figures and causes the peening head to approach the anvil and upset the eyelet as shown in Fig. 3.

Means are provided for returning the plunger normally to the extended position shown in Fig. 1 in which the peening head extends above the nose of the machine, either directly above as

shown in the solid lines or to the side as shown in dotted line 36 of Fig. 1. These means include spring 48, means mounting the spring upon the first mentioned handle as by screws 50, and means mounting the spring at the other forked end 52 in approximately fixed relation to the plunger as by engagement of the forked end within the annular recess 54 in the part 32.

The operation of the crimping device will be largely evident from the description that has been given.

The eyelets are inserted in the position in which they are to be crimped, that is, through preformed holes in sheet material. With the peening head turned directly over the nose of the crimping device the nose and peening head are then inserted through the eyelet, the wing nut rotated to cause the peening head to extend to the position shown in the dotted line of Fig. 1, and then the handles are squeezed together, to cause the retraction of the plunger and peening head to the position shown in Fig. 3.

The pressure of the handles is then released, the half wing nut rotated slightly to bring the peening head over another part of the rim of the eyelet and the handles again pressed together to crimp this new portion of the eyelet, this cycle of operations being repeated until the inner end of the eyelet is crimped around its complete circumference. When the crimping is completed, the plunger is rotated until the peening head extends over the nose of the machine and against the stop 38. Then the assembly of the nose and head is withdrawn from the grommet, the width of the peening head adapting it, when turned over the said nose, to pass through any eyelet of size to receive or permit withdrawal of the nose itself.

The spring forces the stop 32 towards the lower end of the hole in which the plunger is disposed. This causes a corresponding movement of the plunger 18 and of the part 44 of the second handle, so that when the hand pressure is released from the handles, the handles become fully separated and the plunger comes to extend above the end of the nose of the machine as shown in Fig. 1.

Materials of construction of the various parts are of kind ordinarily used in such parts. Thus the spring may be of spring steel and other parts of the device of steel, stainless steel, or relatively hard brass.

The device is dependable in operation and is convenient in effecting blind crimping in which the peening head must be inserted from the outside through the eyelet and caused to extend over the inner end of the eyelet.

It will be understood also that it is intended to cover all changes and modifications of the example of the invention herein chosen for the purpose of illustration which do not constitute departures from the spirit and scope of the invention.

What I claim is:

1. A crimping machine for upsetting metal and like eyelets comprising a nose provided with a longitudinally extending slot opening on one side only of the nose, said nose being of a size to pass through the eyelet, a body of the machine continuous with the nose but of larger cross section

and provided with a hole in line with the slot, an anvil portion of the body disposed around the base of the nose, a plunger mounted slidably and rotatably within the said hole and slot and extending at one end beyond the nose and at the other beyond the body, a peening head extending to one side of the forward end of the plunger, means for rotating the plunger so that the attached peening head is caused, alternately, to extend over the end of the nose and to one side thereof, and means for forcing the peening head, when the head extends to the said one side, towards and near to the anvil, so as to provide the desired crimping action, the peening head being of length to terminate at a position not beyond the side of the said nose when the head is turned over the nose and the said slot being offset with respect to the center line of the nose.

2. A crimping machine as described in claim 1, the said slot extending into the nose from one side thereof only to a depth approximately equal to the diameter of the plunger and the peening head being generally hook-shaped and of width not greater than the width of the said nose, so that when the peening head is rotated in direction to cause it to extend over the said nose, then the peening head and nose assembly is adapted to be passed through any eyelet of size to pass the nose itself.

3. A crimping device as described in claim 1, the said means for forcing the peening head towards the anvil including a pair of handles extending in direction generally longitudinal with respect to the direction of the said plunger, one handle being continuous with the said body, means mounting the other one of the handles at its end pivotally on the one handle continuous with the body, a stop on the plunger, and an intermediate part of the said other one of the handles resting on the said stop and on the side thereof towards the peening head so that, as the said other one of the handles is forced in the direction of the handle continuous with the body, the stop and attached plunger are retracted within the said body of the machine so that the peening head is drawn towards the anvil.

4. A crimping device as described in claim 3, including a spring member and means mounting the spring member at one end on the said stop and at the other end on the handle continuous with the said body, so that the spring applies force holding the peening head normally in fully extended position beyond the said nose.
